UNITED STATES PATENT OFFICE.

BERNARD T. STEBER, OF UTICA, NEW YORK.

MATCH-MACHINE.

SPECIFICATION forming part of Letters Patent No. 595,978, dated December 21, 1897.

Application filed July 13, 1897. Serial No. 644,406. (No model.)

To all whom it may concern:

Be it known that I, BERNARD T. STEBER, a citizen of the United States, residing at Utica, in the county of Oneida and State of New York, have invented certain new and useful Improvements in Match-Machines; and I do hereby declare the following to be a full, clear, and exact description of the invention, such as will enable others skilled in the art to which it appertains to make and use the same.

My invention relates to improvements in machines for cutting match-splints, and more particularly to that class of machines which are adapted to cut the splints from blocks of wood by means of a reciprocating cutter and deposit the same in endless carrier-belts by which they are carried through suitable heating and paraffining means and are supplied with heads from a suitable composition-vat.

It consists in certain novel constructions, combinations, and arrangements of parts, which will be hereinafter more fully described and claimed.

In the accompanying drawings, Figure 1 represents a side elevation of my improved match-machine. Fig. 2 represents a vertical longitudinal section through the composition-vat. Fig. 3 is a plan view of the same. Fig. 4 represents a side elevation of the mechanism for cutting the splints and depositing them in the carrier-belt, parts of the same being shown in section. Fig. 5 represents a plan view of a portion of the carrier-chain, showing the cams employed for operating the same. Fig. 6 is a detail sectional view of the reciprocating cutter and a portion of the carrier-chain. Fig. 7 is a detail end elevation of the match-cutting machine, showing the means for removing the matches from the carrier-chain. Fig. 8 is a detail vertical sectional view showing the means for knocking out match-splints which have escaped the delivering mechanism. Fig. 9 represents a top plan view of two groups of slats forming part of the carrier-chain. Fig. 10 represents an end elevation of the same, and Fig. 11 represents a detail view showing one of the slats used in my improved chain. Fig. 12 represents a detail view of the cams for feeding the chain and spreading the slats thereof for ejecting the matches at the end of the machine.

A in the drawings represents a machine for cutting match-splints; B, a heating device; C, a paraffining mechanism, and D a composition-vat.

In manufacturing matches with my improved mechanism I preferably employ an endless chain E, which is adapted to pass through the machine A, where it receives rows of match-splints from a reciprocating cutter mounted therein. After the chain has received the said splints it carries them over a heater B, which is provided with suitable heating means, which consist, preferably, as indicated in the drawings, of coil-pipes, as b, connected with any suitable steam or hot-water heating mechanism. After passing over the heater B the matches are carried to the paraffining mechanism C, which consists of a tank c, holding paraffin or a similar solution and being provided with chain-depressing means, as c'. This chain-depressing means consists of pivoted links c² c², having rollers c³ at their lower ends, which bear upon the upper side of the chain and depress it sufficiently to cause the ends of the match-splints to be dipped into the solution of paraffin. From the paraffining device the chain passes to the composition-vat D, which forms an important feature of my invention.

The composition-vat D consists, preferably of an outer tank, as d, mounted upon suitable standards, and an inner reciprocating tank d''. The outer tank is adapted to hold water, which surrounds the inner tank and which is kept in a heated state, preferably by passing a heating-coil through the bottom of the said tank, as at d². The inner tank d' is adapted to hold a suitable composition for providing igniting-heads for the matches. In order to place this composition upon the match-splints, I employ a roller, as d³, mounted upon a shaft d⁴, which has bearings formed upon the outer tank d. Power is communicated from the shaft d⁴ from any suitable means in order to rotate the roller d³. The roller d³ is so arranged as to have its periphery constantly dipping into the composition in the vat below it, and as the roller is revolved the composition will be carried up upon the periphery thereof and will be brought in contact with the lower ends of the match-splints in the carrier-chain E, which is arranged to

pass just over the roller. In order to prevent clogging and an excess of composition from sticking to the roller d^3 , I provide an adjustable scraper d^5 , which is adapted to fit the 5 periphery of the roller, as at d^6 , and is secured to a cross-bar d^7 . The cross-bar d^7 is adjustably secured to the outer tank, as illustrated in Fig. 3 of the drawings. It will be observed that this form of scraper not only 10 removes the excess of the composition from the periphery of the roller, but is also adapted to scrape the composition from each side of the roller. In order to reciprocate the inner vat d' , a pitman, as f , is pivotally secured, as 15 at f' , to one end of the said vat. This pitman extends out over the edge of the outer tank d and is secured to a crank, as f^2 , from which it receives its motion. The crank f^2 is mounted upon a shaft f^3 , which is suitably carried 20 by an arm f^4 , which is fastened to the outside of the tank d . A power-wheel f^5 is secured to the shaft f^3 and is adapted to receive motion from any suitable power mechanism, as by the use of a belt. In order to movably 25 support the vat d' within the outer tank d , rollers or small wheels, as f^6 f^6 , are preferably secured upon the bottom of the said vat. These rollers run upon the bottom of the tank d , and thus permit the vat d' to be reciprocated with very little friction. In order to 30 assist in keeping the composition in the vat in a thoroughly-agitated condition, I provide a stationary agitator G , which is supported just above the bottom of the vat d' . This 35 stationary agitator may be constructed in any desired form; but I find it advantageous to use simply slats g , united and held together by means of rods $g' g'$, which run through a perforation in each of the slats g . Small 40 spacing-sleeves $g^2 g^2$ are preferably placed between the slats to hold them at the desired distance apart. These parts after being assembled are all clamped together by means of nuts $g^3 g^3$, applied upon the ends of the 45 rods or bolts $g' g'$. To one end of the agitator is secured a supporting-arm g^4 , which extends upwardly above the vat d and is rigidly secured to another arm g^5 . The outer end of the arm g^5 is preferably pivotally secured to 50 the outer tank d , as at g^6 . By this simple construction the agitator can be held stationary in the bottom of the vat d , and when it is desired to clean the same it can be swung upwardly and outwardly upon the pivot g^6 , 55 which will greatly facilitate the cleaning operation.

After receiving the heads of igniting material from the composition - vat the match-splints are carried by the chain B back and 60 forth upon a suitable drying - frame, as N . This drying-frame is preferably made of suitable length and is provided with supporting-shelves, as $n n'$, over which the chain passes. Standards, as $n' n'$, support the shelves and 65 may be constructed in any suitable and desired manner. Pulleys, as $n^2 n^2$, may be

mounted upon the frame N to assist the chain in passing through the drying-frame N .

In order to prevent the necessity of the operators using the machine having to go from 70 the composition-vat clear around the end of the frame N , I arrange the supports $n' n'$ near the vat D , so as to form an opening, as N' . By the use of this opening an operator can pass quickly from one side of the machine to the other without going around the ends thereof.

The chain E is preferably of the endless type and consists of a series of slats grouped together, so as to receive the match - splints 80 between them. These slats are preferably held together upon the said splints by means of suitable springs interposed between said groups. These groups of slats may be linked together in any suitable way so as to form 85 flexible joints between the same and thereby form a flexible carrier - chain. In order to move this carrier-chain along its path, I employ a series of cams, as H , which are preferably mounted upon the splint-cutting mechanism. In employing a splint-carrying chain of this character and one which is adapted to be moved by means of cams interruption in the operation of the machine is apt to occur 90 by some of the slats forming a component part of the said chain being broken, and when the broken slat reaches the feeding-cams there is nothing for the cam to engage and the chain is therefore caused to halt. In order to obviate the chance of any such difficulty, I have conceived the idea of employing two or more cams so arranged as to engage the slats of the chain to feed it forward. As shown in Figs. 4 and 5 of the drawings, 95 two cams, as $h h'$, are employed at the forward end of the splint-cutting machine and arranged upon horizontal shafts $h^2 h^2$. The cams $h h'$ are located just above the splint-cutter a and are formed with spiral flanges $h^3 h^3$, which are made tapering in thickness, 100 as illustrated, whereby the said flanges are adapted to pass between the slats of the carrier - chain and open them to receive the splints brought up by the cutter a . The cams $h h'$ are also provided with spiral flanges $h^4 h^4$; 105 but these flanges are not made tapering and do not pass between the slats of each group, but preferably engage the outer surfaces of the slats of each group, thus being adapted to feed the chain forward without opening the 110 slats. It will be apparent from this construction that should a slat become broken one set of cams would always engage sound slats and move the chain forward irrespective of the 115 broken slat. The cams are adapted to be revolved by any desired or suitable mechanism, preferably by that illustrated in the drawings. The cams $h h'$ may be secured upon the shafts $h^2 h^2$ at any desired point thereon and upon 120 either side of the cams $h h$ without departing from the spirit of my invention.

After the chain E has received the match-

splints from the cutter and they have been suitably treated and provided with heads and passed through the drying mechanism they are again returned to the machine A and 5 pass to the delivering mechanism. As shown in Figs. 7 and 4 of the drawings, cams i i' , similar to cams h h' , are used at this end of the machine A to assist in feeding the chain and to open the slats for ejecting the completed 10 matches. The cams i i' are provided with flanges of tapering thickness, which are adapted to open the slats forming the chain E, so that the matches may be forced out from between the slats, as by a platen I, Fig. 4. The 15 platen I may be reciprocated in any suitable manner, and the completed matches are preferably ejected upon an endless belt i^2 , which serves to collect them, so that they may be gathered and placed in boxes. The cams i i' 20 are preferably mounted upon the same shafts that carry the cams h h' , but are provided with flanges which do not taper, they being constructed to feed the chain forward without opening the slats.

25 It will be evident that any number of cams may be employed for feeding the chain forward without departing from the spirit of my invention.

After the matches have been ejected from 30 the chain carrier E the chain, with its empty groups of slats, passes again to the splint-cutter a to receive a new charge of splints. The cutter a may be formed in any suitable manner and is preferably constructed so as to cut 35 a number of splints at a time. The cutter a is mounted upon a machine A, as at a' , and is connected to a crank a^2 by means of a pitman a^3 . The crank a^2 is formed upon a shaft a^4 , provided with a belt-wheel a^5 . The belt- 40 wheel may be connected with any suitable power mechanism and the shaft a^4 be thus rotated to impart the desired reciprocating movement to the cutter a. As it is necessary for the cutter to come quite close to the chain 45 E in depositing the splints therein, it is necessary for the same to pass up between two rows of splints in the said chain, as shown in Fig. 6 of the drawings. On account of the small space between the rows of splints the 50 bar a^6 , to which the cutter a is secured, is of necessity made narrow, and in order to increase the strength of the said bar a^6 I preferably bevel the lower edge thereof, as at a^7 , and in this way obtain a bar of greater depth and 55 consequently possessed of greater strength.

In using chains in match-machines of this kind it often happens that the mechanism for delivering the completed matches fails to eject all of them and now and then leaves 60 a few of the splints sticking in the said chain. It has been common to use a revolving cutter-head provided with knife-edges, which are caused to revolve in close proximity to said chain below the delivery mechanism, so 65 as to catch any stray matches and knock them out of the chain. In accomplishing this purpose I mount a revolving cutter-head, as J,

upon the machine A below the ejecting-cams i i' . The cutter J is provided with a series of blades, as j j , as shown in Figs. 7 and 8 of the drawings, which when the cutter-head is revolved comes in close proximity to the chain E. In order to prevent the chain from being forced away from the cutter J, a track portion j' is formed on the frame A just to 70 the rear of the chain. In order to prevent the blades j j from coming in contact with the chain E, I provide the cutter-head with end disks, as j^2 , which will bear against the chain, but will hold the blades at a suitable distance 75 therefrom. The cutter-head J may be revolved by any suitable and well-known means. In order to prevent any back movement of the chain E on account of the action of the cutter J, I employ pivoted dogs, as j^3 j^3 . The 80 dogs j^3 j^3 are preferably angular in shape and pivoted to the frame A below the ejecting mechanism and are adapted to be held in constant contact with the chain E by means of the weight of their outer ends. It will be 85 seen that after each group of slats passes the dogs j^3 they immediately assume a position behind the same, so that the slat cannot make a retrograde movement.

While I may employ a chain of any suitable construction in the use of my machine, yet I prefer to use a chain formed of slats and links, as illustrated in Figs. 9, 10, and 11 of the drawings. In this construction the chain is formed of links e e , pivoted together, as at 90 e' e' , and provided with central openings to receive the ends of the slats. The slats are arranged in groups, preferably two in a group, the slat e^2 being formed of the same thickness throughout and provided upon its inner surface with a piece of felt or other soft material, as e^4 . The other slat e^3 of each group is preferably thickened at its central portion to give it strength, the said thickened portion tapering, as at e^5 , to form end portions of the 100 same thickness as the slats e^2 . By making the tapered portion of the slats e^3 curved, as shown in the drawings, instead of making a square shoulder, as might be done, the end portion of the slats are greatly strengthened, 105 and I prefer to employ this form of construction. As shown in Fig. 11 of the drawings, the slats are preferably shouldered, as at e^6 e^6 , the outer reduced ends of said slats being adapted to project through the central openings in the links e e . The openings in the 110 links e e are made to fit the width of the ends of the slats, as e^7 , but are preferably enlarged, as at e^8 , so that a slat may be withdrawn from the links at this point, if it is desired. The 115 inner surface of the slats e^2 e^3 are preferably provided with serrations or grooves to receive the match-splints. Springs, as e^9 e^9 , are interposed between the links e e and slats e^2 , so that the said slats e^2 are normally held 120 against the slats e^2 and e^3 . By this construction a very superior chain is formed and one which can readily be opened to receive match-splints and yet effectively hold the same after 130

being deposited therein. It will also produce a chain which is so constructed as to permit of broken slats being easily withdrawn without taking the links apart and new slats 5 to be substituted in place of the same.

As illustrated in Fig. 7 of the drawings, the pairs of cams *i* are made with tapering flanges, the enlarged ends of which tapering flanges are sufficiently wide to spread the slats of the 10 chain to permit of the matches being ejected therefrom. The pairs of cams *i' i'*, as seen in the same figure, are provided with flanges, which are made quite thin and preferably of a uniform thickness throughout. This is 15 quite an important feature of the machine, in that the flanges of the cams *i' i'* may be passed between the members of each group of slats either accidentally or designedly, and if they were not made thin they would operate 20 to spread the slats of the chain before the proper time and thus render the matches liable to be thrown out of the chain before it is desired that they should be. As illustrated in Fig. 12 of the drawings, it will be 25 seen that the flanges of the cams *i' i'* may pass between the slats of the chain without spreading them so as to drop the matches, and the said cams will still be just as effective in assisting to feed the chain forward as when 30 their flanges bear on the outside of the groups of slats, as shown in Fig. 7.

Having now described my invention, what I claim as new, and desire to secure by Letters Patent, is—

35 1. In a match-making machine, the combination with means for cutting match-splints, of a chain adapted to receive the said splints comprising groups of fixed and movable slats, pairs of cams for feeding the chain forward, 40 one of each pair being provided with flanges located so as to spread the slats to receive the splints and to feed the chain forward and the other pair of cams being adapted to engage the outer surfaces of the groups of slats 45 to serve as an auxiliary feed, and means for rotating said cams, substantially as described.

2. In a match-making machine, the combination with a suitable means for cutting match-splints, of a chain consisting of a series 50 of fixed and movable slats for holding the said splints, pairs of cams, one of each pair located to engage between the slats and open and feed them forward and the other to engage the rear of the slats to serve as an auxiliary feed, and means for rotating the said 55 cams, substantially as described.

3. In a machine for making matches, the combination with a suitable cutter for cutting match-splints, a chain comprising fixed and 60 movable slats, means for providing the splints with igniting-heads, and pairs of worm-cams, one of each pair located to engage between the slats at the end of the machine whereby the completed matches may be ejected from 65 the chain and the other adapted to engage the slats to serve as an auxiliary feed, substantially as described.

4. In a machine for making matches, the combination with a suitable cutter for cutting match-splints, a chain having co-operating 70 fixed and movable slats, means for receiving the splints, means for providing the splints with igniting-heads, pairs of worm-cams, one of each pair located to engage between the slats at the end of the machine to open them, 75 whereby the completed matches may be ejected and the other adapted to engage the slats, but not opening them, to serve as an auxiliary feed, and shafts for supporting and rotating the said cams, substantially as described. 80

5. In a machine for making matches, the combination with a chain for receiving the same, co-operating fixed and movable slats on the chain, and pairs of worm-cams at the 85 end of the machine, one of each pair being provided with wide flanges to engage between the slats for opening and feeding them forward whereby the matches may be ejected and the other pair having thin flanges whereby they may engage between the slats without opening them yet serving as an auxiliary feed, substantially as described.

6. In a machine for making matches, the combination of a cutter for cutting match-splints, a carrier-chain adapted to receive the 95 said splints, means for ejecting the completed matches from the chain and a cutter-head mounted below the ejecting means consisting of a head carrying blades adapted to knock 100 out any splints or matches which may escape the ejecting means and disks upon the ends of said head for holding the blades away from the said chain, substantially as described.

7. In a machine for making matches, the 105 combination of a carrying-chain, means for placing match-splints therein, and means for ejecting the completed matches therefrom, a cutter-head adapted to knock out any matches which have escaped the ejecting means and 110 means for preventing a retrograde movement of the chain consisting of pivoted dogs adapted to engage the said chain whereby the chain is free to move forward but cannot move back, again, substantially as described. 115

8. In a machine for making matches, the combination with a suitable cutter, of a chain consisting of links pivoted together, groups of smooth and grooved slats mounted in said links, springs also mounted in the said links 120 and adapted to bear upon the said smooth slats for holding them against the grooved slats, the grooved slats of each group being thickened to strengthen them and being provided with tapering end portions whereby the 125 said grooved slats will not occupy more space in the links than the smooth ones, substantially as described.

9. In a machine for making match-splints, the combination with a suitable cutter of a 130 chain carrier consisting of a series of slats for holding the match-splints, links pivotally secured together and provided with central apertures, one portion of the said apertures be-

ing adapted to receive the reduced ends of the said slats and the other portion of the said apertures being enlarged whereby the whole slat may be withdrawn through the said enlarged portion and means for holding the said slats together substantially as described.

10. In a machine for making matches, the combination with a splint-cutting mechanism, of a chain for receiving the said splints, means for providing igniting-heads for said splints comprising a vat adapted to hold water, an inner movable vat adapted to stand in the water, means for reciprocating the said movable vat, a stationary agitator mounted in the said movable vat and a roller for carrying the composition upward against the match-splints, substantially as described.

11. In a machine for making matches, the combination with a suitable splint-cutting mechanism, of a chain for receiving and carrying the same, a vat for supplying igniting material to said splints comprising a reciprocating vat adapted to hold a suitable igniting composition, rollers upon said vat for movably supporting the same, a pitman se-

cured to said vat at one end and to a crank at the other, whereby a reciprocating motion may be imparted to said vat and a roller for carrying the composition to the ends of the matches, substantially as described.

30

12. In a match-making machine, the combination with a suitable splint-cutter, of a chain for receiving and carrying the same, a composition-vat comprising an inner movable vat and an outer stationary vat, means for reciprocating the inner vat, a stationary agitator pivotally mounted upon the outer vat whereby the same is adapted to be held stationary in the bottom of the movable vat or may be turned upwardly upon its pivotal point for cleaning the same when desired and a roller for carrying the composition to the ends of the match-splints, substantially as described.

35 40
In testimony whereof I hereunto affix my signature in presence of two witnesses.
